UNITED STATES PATENT OFFICE.

HOWARD E. BAACK, OF CHICAGO, ILLINOIS, ASSIGNOR TO PATENT ENGINEERING COMPANY, OF CHICAGO, ILLINOIS, A CORPORATION OF ILLINOIS.

PUTTING GREEN.

Application filed July 12, 1926. Serial No. 121,870.

This invention relates in general to indoor games and more particularly to a game simulating a golf putting green designed to be employed with clubs and golf balls.

5 The invention has for its object the provision of a mechanism for practicing putting, which will at the same time afford sufficient amusement to stimulate practice.

10 Another object of the invention is an improved parlor game designed to employ as part of its equipment the clubs and balls usually employed with golf.

15 An article made in accordance with the present invention comprises a frame provided with means for holding it at an angle from the floor and having a plurality of holes therein spaced in a predetermined manner. Means is also provided whereby when a golf ball is shot or putted into one of the holes it will be 20 discharged onto the floor or a suitably provided receptacle.

25 The other equipment employed is a plurality of golf balls and the usual golf putters or other clubs fashioned in substantially the same manner. The equipment is employed in substantially the same manner as when attempting to "sink a putt" on a regular golf course, but is so arranged that a number of 30 novel and interesting competitive games may be worked out to stimulate interest in the putting.

35 The invention will be more fully understood from a consideration of the following detailed description, taken with the accompanying drawing, wherein

Figure 1 is a front view of the "putting green;"

Figure 2 is a rear view thereof;

Figure 3 is a side view thereof, and

40 Figure 4 is a fragmentary sectional view taken on the line 4—4 of Figure 1, showing the arrangement of felt around the holes.

45 As outlined in the above preliminary description of the game, the usual balls and clubs which are employed in golf may be used. The present invention refers to a novel device which for descriptive purposes I term a "putting green." A description of the "putting green" is necessary before the 50 details of the games played therewith may be understood.

55 The putting green comprises a flat section 10 constituting a plane surface, preferably formed of sheet metal and having three rows of holes designated 11, 12—12, and 13—13

respectively. The section 10 has a lower edge 14 bent out of the plane of the main portion of the section and is provided all around with an upstanding edge or shoulder 15. The top, as shown, is of general octagonal shape, but 60 it is apparent that any suitable contour may be provided. At the back of the section 10 is a box-like portion designated 16, said box-like portion having sufficient depth to readily accommodate the ordinary golf ball and communicating with each one of the holes in the section 10.

At the bottom of the oval portion 16 is a chute 17 communicating therewith. The chute 17 has a very slight slant so that golf 70 balls falling through the holes in the section 10 and into the oval portion 16 will roll with very slight force down the chute 17 and be discharged upon the floor or a suitably provided receptacle (not shown).

75 Suitably hinged at the back of the putting green is a supporting member 18, and I provide any suitable means such as a thumb nut 19 whereby when the support 18 is placed at a suitable angle it may be firmly secured at 80 such angle. Underneath the support 18 I provide a thick section of felt 20 to prevent possible injury to the back of the putting green.

85 The entire front of the section 10 and all of the inside of the oval portion 16 are preferably covered with a sound-deadening material, such as felt. In actual practice I have employed a good grade of green felt, thus simulating the color of the usual out-door 90 putting green, and at the same time furnishing substantially the right "roll" for the balls. If a hard material such as wood or metal were employed the balls would roll too quickly and have a tendency to bounce too much, whereas 95 if a softer material such as knitted goods or the equivalent should be placed on the putting green, the action of the balls would be deadening. I have found that a good grade of felt tends to cause a very proper behavior of 100 the balls.

105 In making the felt for the flat section of material I have found that I can allow about one-quarter ($\frac{1}{4}$ ") inch of felt to project over the edges of the holes. This projecting portion can then be pushed down mechanically and will remain at substantially right angles to the main portion of the felt, and have the effect of entirely preventing the possibility of exposing the edges of the metal or other ma- 110

terial in the region of the holes. The projecting portion is adhesively secured to the bottom of the metal portion of the green.

The putting green is placed at an angle to the floor and beneficial results to one's golf game may be obtained by simply attempting to putt a golf ball from some distance away into any selected hole or cup in the putting green.

10 Since it is much more interesting to have some species of competition, I have worked out a number of games, two of which I have termed "Rug golf" and "Putt-it-in" respectively. Sample rules which I have made for 15 these two games are as follows:

RULES OF RUG GOLF.

The afterdinner game.

No limit to number of players,
20 Players draw lots to determine order in which each will play,

On a line ten feet from rug golf green, first player places six golf balls in a row. Distance between balls should average two to 25 three inches.

Player starts at end of row and shoots each of six balls before next player shoots.

Player is allowed but one shot at each of the six balls played during each round.
30 During entire game each player in turn shoots six rounds of six balls or 36 balls during game.

Record of all players' scores are kept and 35 player having highest score at end of sixth round is winner.

In the game of "rug golf" strokes are not counted.

Winner is determined entirely on basis of 40 score value of holes in which balls are sunk as shown on chart below.

Chart of course.

If putted into this "Little Joc" hole	○ (small)	it scores 25.
If putted into one of these "Big ten" holes	○ (intermediate)	it scores 10.
45 If putted into one of these "Grand Canyon" holes	○ ○ (large)	it scores 5.

RULES OF PUTT-IT-IN.

The game for the happy crowd.

50 No limit to number of players,

Players draw lots to determine order in which each will play.

Only one ball is used.

Players places ball for first shot ten feet 55 from putt-it-in green.

If player does not hole out on first shot the ball is again played from where it stops after rolling back from the green. Player never places ball except for first shot.

60 Player continues to shoot ball from spot it rolls from green until holed out.

Each succeeding player shoots in turn and shoots ball until holed.

If ball is shot beyond putt-it-in green it is 65 considered in the bunker and each stroke

necessary to bring ball back into putting position is counted.

Every stroke taken by player is counted and when player holes out add to number of strokes taken the stroke penalty of the hole in which the ball is sunk. Chart below shows penalty for each hole.

70 Player having lowest score wins.

Chart of course.

If sunk in this Birdie hole	○ (small)	add 2 strokes.
If sunk in any one of these Par holes	○ (intermediate)	add 3 strokes.
75 If sunk in any one of these Bogey holes	○ ○ (large)	add 4 strokes.

(The holes are shown in substantially the 80 positions on which they appear on the putting green.)

It is obvious, however, that other types of games may be worked out of the putting green employed for practice only, without any competitive features.

It will be noted that the holes in the three rows, namely, upper, intermediate and lower rows are of different size, the upper hole which I term "Little Joe" or the "birdie" hole 90 is the smallest hole, and in a putting green made in accordance with the invention which I have used in actual practice is two and seven-eighths (2 $\frac{7}{8}$) inches in diameter. On the same putting green, the intermediate 95 holes, the "big ten" or par holes, are three and one-quarter (3 $\frac{1}{4}$) inches in diameter, and the lower or larger holes, the "Grand Canyon" or "bogey" holes, three and three-quarters (3 $\frac{3}{4}$) inches in diameter. These measurements have been determined by careful experiment, but it is obvious that other dimensions may be employed while still maintaining the graduation in sizes.

100 The difference in the value of the holes is determined not only by the size of the holes but also by their location on the green, it being apparent that it is more difficult to sink a putt in the upper hole than in the lower holes, and more difficult to sink a putt in one of the intermediate holes than in the very lowest holes. To reach the "birdie" hole the player must make the ball pass right between the two largest holes, thereby running into danger of dropping the ball into one of these holes. At 115 the same time, he must hit the ball harder to cause it to travel all the way up on the green and when hitting it in this way, it is rather easy to hit the ball too hard and cause it to strike the edge of one of the holes and bound to the side or in back of the putting green.

120 The arrangement of the greens in this manner and the graduation in sizes makes it possible for a player to elect the manner in which he will play the game, depending on the score of his opponent. It is analogous to a player on an actual golf course having the choice of playing straight across a rough portion of the course where he must drive the green, or get into serious trouble, or on the other hand 125 130

playing a possible "dog-leg" in which he has two easy drives which will not lead him into trouble. It is situations such as these that makes the game of golf so interesting, and it 5 will be seen that the same matter of choice may be had with a putting green constructed in accordance with my invention.

Although I have explained the details of my invention rather fully in order to simplify 10 an understanding of the same, it is obvious that I do not wish to be bound by this specific arrangement since the grouping and size of the holes and many other structural details may be modified without departing 15 from the spirit and scope of the invention.

I claim:

1. A putting green comprising a flat section of material, with holes therein and a sheet of felt thereon, there being holes in the felt registering 20 with the holes in said flat section of material, and means for supporting said flat section of material at a predetermined angle,

the holes in the felt being cut smaller than the holes in the flat section of material, and being pressed down mechanically to prevent exposure of the edges of said holes. 25

2. A putting green as defined in claim 1 wherein said portion of felt around said holes is bent around and adhesively secured to the underside of said flat section of material. 30

3. In a putting green, the combination with a plane having a plurality of holes therein, a member disposed on the underside of said plane to receive any balls passing through said holes, a spout communicating with said member to direct the return of the balls received by said member from all of said holes, means for maintaining said plane in an inclined position so that an edge thereof will merge with a flat putting surface, and a felt 35 covering for said plane and interior of said member. 40

HOWARD E. BAACK.
